DISPENSER

Guy Amos Rhodes, Milford, Ohio

Application December 31, 1942, Serial No. 470,857

6 Claims. (Cl. 65—45)

This invention aims to provide a container which is normally closed, airtight, novel means being provided for rendering the container substantially hermetic, and novel means being supplied whereby the container may be opened to permit the outward passage of its contents. Such a structure is desirable, for example, when embodied in a salt or pepper shaker, it being well known that these condiments, and particularly salt, will not flow readily if damp, and many substances being subject to deterioration unless kept dry. Another object of the invention is to supply novel means for measuring the quantity of material dispensed.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in longitudinal section, a device constructed in accordance with the invention;

Fig. 2 is a cross section on the line 2—2 of Fig. 1;

Fig. 3 is a view similar to Fig. 1, but showing the device as it will appear whilst the material is flowing out of the container;

Fig. 4 is a bottom plan;

Fig. 5 is a transverse sectional view showing how the diaphragms may be constructed before being placed in the container;

Fig. 6 is a vertical section showing a modification, parts being broken away in Figs. 6 and 3.

The numeral 1 marks a hollow, tubular body, made of any desired material, and of any preferred cross section, the body being rigid. An upper retainer 2 is removably mounted, by threading or otherwise, on the upper end of the body 1, and has a central opening 3, defining an annular, overhanging flange 4. A resilient, upper diaphragm 5, preferably made of rubber, is marginally bound between the flange 4 and the upper end of the body 1 and has an upwardly bulged portion 6 extended into and through the opening 3.

A lower retainer 7 is threaded on the body 55

1 and is provided with a central opening 8 defining a flange 9. About the opening 8, the flange 9 has an upwardly extended ridge 26 of small height. A lower, resilient diaphragm 10, preferably made of rubber, is marginally bound between the retainer 7 and the end of the body 1. The diaphragm 10 rests on the flange 9 and the rib 26. The lower diaphragm 10 has an upwardly bulged central portion 11, in which is located a normally closed slit 12. The slit 12 is disposed directly above the opening 8 in the lower retainer 7.

A rigid plunger 16 is provided. The upper end of the plunger 16 is received in the bulged portion 6 of the upper diaphragm 5. The lower end of the plunger 16 rests on the bulged portion 11 of the lower diaphragm 10. There is a cavity 17 in the lower end of the plunger 16, and the plunger has downwardly and inwardly inclined passages 18 establishing communication between the interior of the body 1 and the cavity 17. The plunger 16 should be made of light material. A hub 27 is secured to the plunger 16 and carries radial fins 15 having V-shaped edges 28 which engage the inner surface of the body 1, to guide the plunger as it reciprocates, and to keep the plunger centered.

It will be noted that the upper diaphragm 5 constitutes a gasket, located between the upper end of the body 1 and the flange 4 of the upper retainer 2. The lower diaphragm 11 exercises a similar office with respect to the flange 9 of the lower retainer 7 and the body 1. The slit 12 in the lower diaphragm 10 is normally closed, as in Fig. 1, and it will be noted that air cannot find its way into the container, when the parts are arranged as shown in that figure.

When the operator pushes down on the bulge 6 of the upper diaphragm 5, the plunger 16 is carried downwardly, and the slit 12 is opened, as shown at 19 in Fig. 4. Salt or the like, within the body 1, then can flow through the passages 18 and the cavity 17, into and through the opened slit. When pressure on the bulged portion 6 of the upper diaphragm 5 is relieved, the central portion 11 of the diaphragm 10 springs upwardly, closing the slit 12 and bringing about a lifting of the plunger 16 to the position of Fig. 1. The ridge 26 on the flange 9 of the retainer 7 aids in the closing of the slit 12 in the diaphragm 10.

In Fig. 6, which shows a modification, parts hereinbefore described have been designated by numerals already used, with the suffix *a*. In this form of the invention, a measuring of the quantity delivered is effected.

In this form of the invention, the bulged portion of the lower diaphragm 10 is represented by an upstanding boss having a measuring compartment 21, forming an upper wall 24 in the boss, and a lower wall 23 therein. The boss 20 is cut transversely, to form a normally open upper slit 22 in the upper wall 24 of the boss, and to form a normally closed lower slit 25 in the lower wall 23 thereof.

It will be noted that the measuring compartment will fill with material, through the open, upper slit 22, and when the boss 20 is pushed down, through the instrumentality of the plunger 16a, the upper slit will close, and the lower slit 25 will open to permit the material to run out.

The diaphragm 10 may be made of a semi-cylindrical piece 26' of rubber, specifically, one portion of a tube or hose that has been severed lengthwise. A short cut 27' is made in the member 26, midway between its longitudinal edges. When the member 26' is in place, as in Fig. 1, and has become the diaphragm 10, the central portion of the diaphragm will bulge upwardly, the cut 27' becoming the closed slit 12.

The fins 15 serve not only to guide the plunger 16 but also aid in keeping the salt finely divided.

Although the device is closed against the entrance of air when not in use, a small quantity of air will enter when the diaphragm 10 is opened as in Fig. 3, and a small quantity of air will enter to replace the material that runs out.

The dispenser shown in this application will be found peculiarly useful aboard ship, it being a matter of common knowledge that the moisture content of the air is so great at sea that salt will not run out of an ordinary shaker, the practice being to serve salt in an open bowl.

Having thus described the invention, what is claimed is:

1. A dispenser comprising a hollow body, a resilient, imperforate diaphragm mounted on the upper portion of the body, a resilient diaphragm mounted on the lower portion of the body and having a normally closed slit, and a plunger slidably mounted in the body and engaged between the diaphragms, in close vicinity to the slit, the plunger constituting means for opening the slit when the upper diaphragm is depressed.

2. The dispenser of claim 1, and wherein the

plunger has a cavity in its lower end, the cavity being disposed about the slit, the plunger having a side passage leading from the interior of the body to the slit.

3. A dispenser constructed as set forth in claim 1, and wherein both diaphragms have upwardly bulged portions, the slit being located in the upwardly bulged portion of the lower diaphragm, and the upper end of the plunger engaging the upper diaphragm within the upwardly bulged portion of that diaphragm.

4. A dispenser constructed as set forth in claim 1, and wherein the lower diaphragm is of a common thickness throughout its extent.

5. A dispenser comprising a hollow body, a resilient diaphragm mounted on the lower portion of the body and provided with an upstanding boss having a measuring compartment forming an upper wall and a lower wall in the boss, the lower wall having a normally closed slit, and the upper wall having a normally open slit, and a plunger slidably mounted in the body and having its lower end engaged with the boss in close relation to the slit, whereby the plunger will constitute means for pushing the boss downwardly, thereby to open the normally closed slit and to close the normally open slit, and means for guiding the plunger for straight line movement in the body.

6. A dispenser comprising a hollow body, an upper, resilient diaphragm mounted on the upper portion of the body, a lower retainer on the lower portion of the body and having an opening defining a flange in the lower retainer, the flange having an upwardly extended ridge of small height disposed close to the opening, a lower resilient diaphragm bound between the flange and the lower end of the body, the lower diaphragm being bulged upwardly over the ridge, the bulged portion of the lower diaphragm having a normally closed slit, a plunger extended between the diaphragms and constituting means for opening the slit when the upper diaphragm is pushed downwardly, and the resiliency of the lower diaphragm being sufficient to close the slit and raise the plunger when the pressure on the upper diaphragm ceases.
